Primary Examiner — Brandon M Rosati*Assistant Examiner* — Marissa J Cash(74) *Attorney, Agent, or Firm* — LKGGlobal | Lorenz & Kopf, LLP(57) **CLAIM**

The ornamental design for a side wall of an aircraft cockpit, as shown and described.

DESCRIPTION

FIG. 1 is a front perspective view of a side wall of an aircraft cockpit;

FIG. 2 is a front view thereof, the back view forming no part of the claimed design;

FIG. 3 is a first side view thereof, the second side view forming no part thereof; and,

FIG. 4 is a top view thereof, the bottom view forming no part of the claimed design.

The even length broken lines structure and environment that form no part of the claimed design. The single dash and single dot broken lines indicate boundaries of the claimed design that form no part thereof.

1 Claim, 4 Drawing Sheets(56)
